Suginami-ku, Tokyo, Japan

Filed June 30, 1960, Ser. No. 61,168

Claims priority, application Japan Jan. 14, 1960

Term of patent 14 years

(Cl. D70—1)

FIG. 1.

FIG. 2.

FIG. 3.

FIG. 4.

FIG. 5

FIG. 6

Figure 1 is a side elevation of a sewing machine, showing my new design;

Figure 2 is a reversed side elevation thereof;

Figure 3 is a top plan view thereof;

Figure 4 is a front end elevation thereof, as viewed from the left and right of Figures 1 and 2, respectively;

Figure 5 is a perspective view thereof; and

Figure 6 is another end elevation thereof as viewed from the right and left of Figures 1 and 2, respectively.

I claim:

The ornamental design for a sewing machine, substantially as shown.
